UNITED STATES PATENT OFFICE.

WILLIAM F. MARKHAM AND ERNEST S. ROE, OF PLYMOUTH, MICHIGAN, ASSIGNEES TO
MARKHAM AIR RIFLE COMPANY, OF PLYMOUTH, MICHIGAN, A CORPORATION OF
MICHIGAN.

AIR-GUN.

No. 911,056.

Specification of Letters Patent.

Patented Feb. 2, 1909.

Application filed July 30, 1908. Serial No. 446,161.

To all whom it may concern:

Be it known that we, WILLIAM F. MARKHAM and ERNEST S. ROE, citizens of the United States of America, residing at 5 Plymouth, in the county of Wayne and State of Michigan, have invented certain new and useful Improvements in Air-Guns, of which the following is a specification, reference being had therein to the accompanying drawings.

The invention relates particularly to air guns or rifles of the break-down type, and consists in the general construction of a gun of this character, and particularly to the 15 formation of the trigger guard, spring abutment, and the fulcrum on which the stock turns during the breaking down movement.

The invention further consists in various details of construction, and in the novel 20 arrangement and combination of parts as will be more fully hereinafter set forth.

In the drawings,—Figure 1 is a vertical longitudinal section through an air gun embodying our invention; Fig. 2 is a similar 25 view, showing the parts in a different position; Figs. 3 and 4 are sectional perspective views illustrating parts of the gun; and Fig. 5 is a section on line x—x Fig. 1.

In the drawings thus briefly described, A 30 and B represent the usual stock and barrel sections of the gun, pivotally connected to permit of breaking down the stock for the purpose of cocking the gun. The stock is provided with the usual casing or housing C 35 at its forward end, and the barrel is fashioned at its rear end to form a casing D for the reception of the trigger mechanism, the two casings or housings abutting, as indicated in Fig. 1, when the parts of the gun are 40 in their normal position.

E represents the plunger rod or stem (the plunger not being herein shown), terminating in a hook F at its rear end and being of polygonal cross section as indicated in Fig. 3.

G represents the usual compression spring encircling the rod and arranged intermediate disks H I sleeved upon the rod. The disk H is held against outward movement by the spring by a pin a which projects through the 45 stem or rod, while the disk I carries a depending lug or projection b engaging a slot c in the lower part of the true barrel adjoining the casing and is held against rearward longitudinal movement by the spring abutment J, more fully hereinafter described.

K is a link forming the connection between the plunger rod and stock engaging at its forward end the loop section F of the rod, and being pivoted at its rear end within the housing C by a transverse pivot d. 60

L represents the usual trigger pivoted within the casing D, and M its spring.

A single member O constitutes the guard for the trigger, the inner abutment for the spring, and the pivot for the stock. This 65 member is preferably in the form of a single bar curved intermediate of its ends to form the trigger guard proper P, while the forward and rearward end portions of the bar constitute the abutment and stock fulcrum. The 70 bar is rigidly secured to the casing D by transverse pins a' b'. The forward end of the bar is upturned, as indicated at J, bearing against the disk I and forming the desired abutment for the spring. The rear end of 75 the bar extends longitudinally, as indicated at Q, and its extremity is connected to the casing C of the stock by a transverse pin e. The lower wall of the casing D is slotted longitudinally to receive the trigger and the 80 ends of the bar O, and the bar is so fashioned that the portions beyond the guard lie within the casing D and the stock housing C, as plainly shown in Fig. 1.

For the purpose of holding the stock in its 85 proper relation to the barrel after the breaking down has been effected, we provide an automatic lock, consisting preferably of lateral projections R formed in the sides of the casing C, preferably by denting in the sides, 90 and a transverse opening S in the fulcrum section of the bar O with which the projections are adapted to engage when the stock and barrel are in operative relation one to the other. 95

The operation of cocking the gun will be obvious from its construction.

What we claim as our invention is,—

1. In a breakdown air gun, the combination with the barrel and stock sections, of the 100 plunger spring, the trigger, and a single bar member constituting a trigger guard, spring abutment and stock fulcrum.

2. In a breakdown air gun, the combination with the barrel and stock sections, of a 105 plunger spring, the trigger, and a single bar rigidly connected to the barrel section fashioned to form a trigger guard, spring abutment and fulcrum for the stock section.

3. In a breakdown air gun, the combina- 110

tion with the barrel and stock sections, of the plunger spring, the trigger, and a single bar rigidly attached to the barrel section having a downwardly curved portion intermediate 5 its ends forming a trigger guard, an upturned forward end adjoining the inner end of and constituting an abutment for the spring, and a rear end portion to which the stock is pivoted.

- 10 4. In a breakdown air gun, the combination with the barrel and stock sections, of a trigger guard, the plunger rod, spaced disk members sleeved upon the rod, a stop upon said rod limiting the outward movement of 15 the forward disk, an abutment carried by the trigger guard limiting the inward movement of the complementary disk, and a compression spring intermediate the disks.
- 15 5. In a breakdown air gun, the combination with the barrel and stock sections, of a 20

plunger rod within the barrel polygonal in cross section, spaced disk members sleeved upon the rod, a pin extending through the rod limiting the outward movement of the forward disk member, a lug upon the complementary disk projecting downwardly within a slot in the barrel section, a rigid abutment adjoining the complementary disk, holding the same against rearward movement, and a compression spring coiled 25 about the rod intermediate the disk members.

In testimony whereof we affix our signatures in presence of two witnesses.

WILLIAM F. MARKHAM.
ERNEST S. ROE.
